METAL WORKING

Claus L. Sporek, Cincinnati, Ohio, assignor to The Lodge & Shipley Company, Cincinnati, Ohio, a corporation of Ohio

Filed Oct. 7, 1958, Ser. No. 765,878

19 Claims. (Cl. 113—52)

This invention relates to the art of metal working and, in particular, relates to apparatus for forming hollow articles from sheet metal blanks.

The term "hollow" as used herewith will be understood to apply to a formed article which is frusto-conical in shape, for example an article similar in shape to a megaphone, and is also meant to include an article which has a hemispherical shape such as a bowl, to an article which is in the shape of a horn and to an article which is generally tubular or cylindrical in shape. It will be understood that the term "sheet metal" includes plate, sheet or plate-like elements when formed by forging, rolling, casting and the like.

In general the apparatus disclosed herein relates to the cold working or flowing of metals by use of a roller or rollers cooperating with a contoured tool or spindle commonly known in the art as "power spinning." Known machines for this purpose comprise, in general, a rotatable spindle which is contoured to the shape of the article desired, a rotatable tailstock for clamping or holding a blank on the spindle together with a roller mounted on a suitable carriage movable over a bed. The carriage is moved so that the roller is brought up to the blank and, while the spindle and blank are rotating, the roller is moved over the surface of the spindle to flow or axially displace the metal of the blank and form the article. Where the article is of conical shape, such machines are arranged so that the bed mounting the carriage can be oriented with respect to the rotational axis of the spindle whereby the carriage moves parallel to the spindle surface. Where the article is to be contoured, the machine may be equipped with a tracer mechanism appropriately moving a roller slide or rest toward and away from the spindle axis. With such tracer control the desired contour is obtained by the resultant roller motion, the carriage imparting to the roller a component of motion along the spindle axis and the roller rest a component of motion transverse the axis.

In copending application 679,551, filed August 20, 1957 (now Patent No. 3,104,640), and being a division of application 454,871, filed September 9, 1954 (now Patent No. 3,114,342), there is disclosed apparatus for working sheet metal blanks by cold rolling or power spinning. The machine disclosed in Patent 3,104,640, as viewed in a general way, makes use of various known elements such as a spindle, tailstock, carriage mounting a roller rest and tracer mechanism to control the in and out motion of the roller rest. As disclosed in that application, such elements have been improved in structure and function, and operation coordinated in a manner previously unknown. Additionally, this application discloses elements of a highly novel nature in the cold flowing art of the kind in question.

The present invention discloses a machine generally along the lines of that disclosed in Patent 3,104,640 in that the machine is particularly suitable for the power spinning of sheet metal blanks into finished articles of the desired shape, and the machine functions in a manner which is largely automatic since the operator merely has to load and remove blanks and initiate the machine operation by pressing a button.

With the foregoing in mind, it is pointed out that the present invention makes substantial improvements both in the apparatus of the art and in the apparatus of Patent

2

3,104,640. In addition, the present invention provides certain wholly novel structures and further provides for new and useful cooperative action between such new structures and/or between improved structures, the foregoing being heretofore unknown and measurably contributing to the advance of the cold working art.

In the forming of articles of the kind discussed herein, it is exceedingly important that dimensional accuracy be maintained, particularly where such articles are for industrial or military use. By dimensional accuracy is meant the overall length of the article and particularly the thickness of its side wall. For dimensional accuracy in the finished article, it is essential to eliminate distortions so as to maintain the desired relative positions of the spindle and roller (or rollers) while the blank is being worked. Despite the required dimensional accuracy, it is necessary, in order to have reasonable costs, that such articles be made on a mass production basis by a fast-operating machine which is largely automatic.

One of the principal objects of the present invention is to provide a fast-operating, automatic machine whose components are constructed and arranged to, in themselves, be strong, rugged and free from distortion and to cooperate with one another in forming an overall structure which functions to maintain the desired dimensional accuracy of the articles being formed.

As one aspect of this, the invention contemplates a novel bed or frame having spaced ends, one of which rotatably mounts a spindle and the other, the driving mechanism for a carriage, the two ends being interconnected by a plurality of columns or tie-in members symmetrically disposed about the rotational axis of the spindle. Preferably there are three columns located substantially at the vertices of a triangle with the spindle axis substantially at the center of the same. This structure provides a strong, rugged, lightweight frame which, in itself, and in cooperation with the carriage carrying the rollers, is conducive to distortion-free operation under high speeds and loads.

Further in this connection, the invention contemplates that the bed and the rotational axis of the spindle be oriented in a true vertical direction. This is of considerable advantage and importance from the standpoint of distortion because there are no gravity cantilever loads on the spindle.

Further the invention contemplates a highly novel carriage structure guided on the bed for up and down movement in a direction along the rotational axis of the spindle. The carriage and its connected components are arranged so that the composite center of gravity lies along the rotational axis of the spindle. Thus, the carriage and the connected components impose no moments on the bed nor on the spindle which otherwise would set up distortions and hence deviations from the desired roller-spindle positions.

The carriage itself has a pair of flat plates disposed on either side of the spindle axis and connected together centrally by a block and further connected together outboard on either side of the block by webbed members which mount the roller rests. The plates, block and webbed members are all interconnected by key and keyway means which contribute to ultimate rigidity, yet provide for the webbed members to be adjustable toward and away from the axis of the spindle for obtaining roller and spindle alignment. The force for moving the carriage is provided by piston and cylinder means interconnected between the carriage and the bed, the piston and cylinder means being arranged so that the resultant force thereof lies along the spindle axis. With this type of arrangement, the driving thrust for the carriage imposes no cantilever loads on the carriage itself, nor on the

bed. Preferably there are two of such piston and cylinder means, the axes of which lie in a plane containing the rotational axis of the spindle and being disposed in such plane at equal distances from the spindle axis.

The roller rests contemplated by the invention are of unique construction comprising cylinders respectively movably mounted on the webbed members and cooperating with pistons fixed to the webbed members, the axes of the pistons and cylinders lying in the above-mentioned plane. The cylinders are movable toward and away from the spindle axis so that the thrusts or loads developed by the pistons and cylinders, in causing roller motion toward and away from the spindle axis, lie in the above-mentioned plane and, therefore, impose no cantilever loads on the carriage. The roller rests mount the rollers so that their working tips and/or rotational axes lie in said plane and, with the thrusts of the piston and cylinder means also lying in said plane, there are no unbalanced radial or cantilever loads on the spindle. The tracer mechanisms operating the roller rests contribute to this condition by controlling the rests so that the working tips of the rollers, during a working operation, are symmetrical with respect to the spindle axis.

The above referred-to Patent 3,104,640 discloses a novel and highly advantageous mechanism which provides that the rollers shall form the article with the required dimensions despite variations in the original thickness of the blank. For this purpose that application discloses mechanism for automatically and correctly positioning the tracer templet at the start of the working operation whereby the rollers will also be correctly positioned, the position of the templet being determined by the thickness of the blank.

It is an object of the invention to provide certain improvements in such mechanism. The invention contemplates that the tailstock and templet both be mounted on a main structure which is movably, yieldably supported by the carriage, the moving and yielding conditions being provided by hydraulic piston and cylinder means. The arrangement provides that the tailstock and templets be fixed connected to that when the tailstock engages a blank on the spindle, the templet is fixed in its correct position while the carriage can continue to move. The arrangement of the invention is particularly suitable for positively driving the main structure in both the up and down direction. This, in conjunction with the vertically-mounted spindle, is highly advantageous from the standpoint of reducing the overall length of the machine. Another advantage in such an arrangement is that the main structure can be independently controlled for the purpose of using the tailstock as a press to push or pull articles or blanks off the spindle, particularly when the blank and/or article is tubular in shape. A further advantage in the present structure is that the tailstock is mounted so that its rotational axis is in a vertical direction and, heretofore, not subject to gravity cantilever loads.

Still another object of the invention is to provide structure so that the rollers, during a working operation, move toward or away from the axis of the spindle in a direction which is oriented at an acute angle to the spindle axis, the preferred angle being 60°. This has special advantage in that the required structure which is relatively light in weight yet able to withstand the thrusts involved without distortion. The preferred angle of 60° is of importance in that it is conducive to a machine of minimum overall length and width.

Another object of the invention is to provide a roller in a machine of the kind described whose rotational axis is oriented at about 75° with respect to the rotational axis of the spindle so that the plane of the roller working tip is disposed at an angle of about 15° to the spindle axis. This is particularly advantageous from the standpoint of the ease of working the metal, hence minimizing the power requirements for driving the rollers.

A still further object of the invention is to provide unique mechanism which is arranged to correctly position a blank on the spindle for the start of the working operation and, when the working operation is over, to move the formed article away from the spindle.

Certain other objects and features of the invention will be apparent from the following description of a preferred embodiment of the invention and drawings wherein:

FIGURE 1 is a front elevational view of a machine constructed in accordance with the invention with the parts shown in position ready to start working the blank;

FIGURE 2 is an enlarged front sectional elevational view, the left-hand half of the view being shown in elevation and the right-hand half in section as indicated by the line 2-2 in FIGURE 4;

The switch trip dogs carried by the carriage and the associated switches also have been diagrammatically indicated;

FIGURE 18 is a similar view showing the position of the parts at the end of the operation of working the blank on the spindle to form a cone;

FIGURE 19 is a similar view showing the position of components of the machine during a portion of the upward travel of the carriage;

FIGURES 20 and 20a taken together schematically illustrate the hydraulic circuits of the machine;

FIGURES 21 and 22 are schematic diagrams illustrating the electrical circuits of the machine; and

FIGURE 23 is a chart showing in a general manner the sequence of machine operation.

Referring now more particularly to FIGURES 1-16, the machine in general comprises: the bed or frame F, the rotatable tool or spindle T mounted on the bed, the carriage C arranged on the bed for movement back and forth generally along the rotational axis of the spindle, roller rests RS mounted on the carriage for back and forth movement transverse the spindle axis and carrying work rollers R, tracer mechanism comprising valves SD

on the roller mounts and the templets or patterns P, the templet mounting structure Te movably mounted on the carriage and carrying the templets P and a tailstock TS, together with blank positioning and stripping mechanism S.

5
The Tool

The spindle or tool T is secured on a vertical shaft 30 having bevel gear drive connection 31 with a drive shaft 32 suitably driven by a motor (not shown). An electrically-controlled clutch 33, diagrammatically shown in FIGURE 1, controls engagement and disengagement of the drive shaft 32 with the spindle 30, and an electrically-controlled brake is provided as indicated at 34. The spindle as shown is conically shaped. However, it will be understood that it may have other shapes depending upon the type of article to be made, for example a cylindrical, horn or bowl shape.

The Carriage

The carriage serves the basic function of supporting the rollers and templets and imparts to the rollers a component of motion in a direction along the spindle axis. The carriage and its connected components are arranged so that the composite center of gravity is along the spindle axis.

The carriage C comprises two rugged substantially triangular flat plates 66 and 67 in spaced parallel relation as viewed in FIGURES 3 and 4, a central support block 68, a side support member 69, a side support 70, all rigidly secured together as explained below.

The block 68 has three spaced, integral collars 68a, 68b and 68c, the collars 68a and 68c having flat sides 71 (FIGURES 8 and 9) abutting the plates 66 and 67 and secured by bolts (not shown) secured in the threaded holes 72. The collar 68b has flat surfaces 73 having keyways 74 therein which receive keys 75 carried by the plates 66 and 67 and extending for the length of the plates.

The block 68 is apertured as indicated at 76 and on top of the block is fixedly secured a head or cap 77. The block and head are slotted at 78 and is best seen in FIGURE 8.

The side support members 69 and 70 are of box-like form rigidly braced by spaced webs 79 to provide a rugged construction and are secured between the plates 66 and 67 by tie rods 80 and nuts 81. The side support members 69 and 70 are provided with keyways 82 for the keys 75.

As best seen in FIGURES 2 and 4, the central support block 68 is positioned centrally lengthwise of the carriage so that the axis of the aperture 76 is substantially coaxial with the rotational axis of the spindle. The plates 66 and 67 and the side supports 69 and 70 are also symmetrically disposed with respect to the spindle axis. This gives symmetrical distribution of forces about the spindle axis. The side support members 69 and 70 may be desirably positioned with respect to the spindle axis by loosening the nuts 81 and moving the same on the keys 75. This adjustment is accomplished by means of end adjusting screws 83 and 84 having their bearings in end cross members 85 and 86 secured to the carriage plates 66 and 67. Elongated slots 87 are provided in the members 69 and 70 to enable the adjustment. The side supports mount the rollers and, by means of the foregoing adjustment, the spacing of the work rollers R, can be altered to suit work pieces and tools of different diameters. This adjustment is also provided to enable leveling of the two rollers so as to work in the same horizontal plane.

The above-described structure and disposition of the carriage are important features of the machine. The plates, the central block and the side supports make a strong and rugged unit capable of taking up the thrusts or stresses produced in a working operation with the very minimum of deflection or distortion. Arranging the carriage generally symmetrically with respect to the spindle axis is conducive to confining resultant thrust load taken by the carriage along the spindle axis so that there are no undesired bending moments. The keys 75 which tie in the various carriage parts perform an important function in permitting adjustability of side supports yet insuring necessary rigidity. In addition to providing a rugged,

deflection-free carriage, the structure is such that the carriage is of relatively small size and light weight. This is important because the carriage is adapted to move in a vertical direction and the necessary power for moving the carriage upwardly is minimized. A distortion- and moment-free carriage is especially important in maintaining the proper relative position of the roller and spindle during a working operation.

6

10
The Bed

The function of the bed is to form a support for the rotatable spindle and for the carriage with its connected elements, the bed being of a structure so that it will not distort under the stresses produced in a working operation nor cause distortions of the spindle mount nor the carriage and its connected parts. Distortionless operation is highly desirable so that there will be no deviations of the desired relative position of the spindle and rollers during a working operation. This contributes to the formation of accurately dimensioned articles.

15
The bed (or frame) comprises a base or support 90, serving as a headstock for the machine, a main upright column or frame 91 (FIGURES 3 and 7) of very rugged construction supported on the base and having a pair of side brace members 92, 92 also secured to the base, a substantial web reinforced top cap or support 93 secured to the top of the column 91 and braces 92, 92, a pair of spaced columns or frames 94 and 94a extending from the base 90 to the cap 93. The column 91 is of heavier construction than the columns 94 and 94a since it serves the function of guiding the carriage and supporting a carriage counter-weight. A pair of brackets 95, 95 extend downwardly from the cap 93. The base has a rugged top plate 90a provided with radial reinforcing webs 90b.

20
As best seen in FIGURE 4, the columns 91, 94 and 94a are disposed on the base 90 so that their vertical axes are located at the points X, Y and Z or at the vertices of a triangle. Also, it will be observed that the columns are arranged with respect to the spindle axis so that the spindle axis lies substantially at the center of this triangle. As will be explained more in detail later, during a working operation the carriage moves the rollers against the blank on the spindle and the reaction of the means moving the carriage is taken on the top cap 93. Thus the stresses of 25 the working operation tend to move the spindle and base away from the top cap. Such movement is prevented by the arrangement and structure of the columns 91, 94 and 94a. The top cap and the base 90 are distortion-free due to the heavy webbed construction described above. I 30 have found that by having the columns spaced in triangular fashion with the spindle axis generally centrally thereof leads to symmetrical load distribution about the spindle axis and resulting in equal loads being taken by the columns so that the resultant forces act along the 35 spindle axis. This prevents undesirable tension or twisting strains in the columns and in the base and top cap. The foregoing is an important part of the invention in that a sturdy, relatively immovable bed prevents distortion between the relative spindle and roller positions desired during the working operation.

The carriage is guided in its up and down motion by means on the main column 91. The guide means takes the form of spaced vertical gibs 96, 96 (FIGURES 3, 4 and 7) cooperating with spaced vertical gibs 97, 97 on 40 the carriage plate 67. The gibs and their supporting shoulders in the plate and column are very accurately machined so that up and down motion of the carriage runs true with the spindle axis.

The Carriage Pistons and Cylinders

45
Up and down movement is imparted to the carriage by means of a pair of hydraulic piston and cylinder devices, one to each side of the spindle axis, comprising cylinders 100, 100 depending from the flanges 101, 101 of the head 50 77 and centered at their lower ends in brackets 102, 102

secured to the block 68 adjacent its lower end. Upper and lower closures 103 and 104 are provided for the cylinders 100 and vertical tie rods 105 tie the cylinders to the flanges 101 (FIGURE 8). Pistons 106, 106 are secured to piston rods 107, 107 depending from the top cap 93 are provided in the cylinders.

Fluid is admitted and exhausted at the upper ends of the cylinders via inlet pipes 110 (FIGURE 2), lateral passages 111, annular chambers 112 and lower ports 113. Fluid is admitted and exhausted at the lower ends of the cylinders by inlet pipes 115 and central passages 116.

When fluid is flowing to the lower ends of the cylinders and exhausting from the upper ends, the carriage is moving down. When fluid flow is reversed, the carriage is moving up. The mass of the carriage (and the connected parts not yet described) are counter-balanced by a counterweight CW connected to the head 77 by a chain and sprocket system generally designated by the numeral 108.

As best seen in FIGURE 4, the pistons and cylinders are disposed the same distance on either side of the rotational axis of the spindle and lie in a plane PSA containing the spindle axis. The forces or thrusts developed by the pistons and cylinders in forcing the carriage down during a working operation react against the top cap 93. With the pistons and cylinders arranged as described, these forces are symmetrically distributed and the resultant force acts along the spindle axis. This is important as it eliminates off-axis thrusts which would otherwise tend to cause deviations in the desired positions of the rollers and spindle during the working operation.

The Roller Rests

The roller rests carry the rollers and are mounted on the carriage side supports 69 and 70 for movement toward and away from the rotational axis of the spindle. Each rest imparts to its roller a component of motion which is transverse to the rotational axis of the spindle (or the direction of carriage movement). Preferably this component of motion is at an angle of 60° acute in the direction opposite to the direction of carriage movement. The movement of each roller rest is controlled by a tracer mechanism. During the working operation the roller rests are moved so that the rollers are symmetrically positioned with respect to the spindle axis. Thus the forces of the rollers counteract one another and there is no unbalanced forces tending to distort the blank or push the spindle off its normal rotational axis.

The left and right hand rollers RS are of like construction and, therefore, only one will be described in detail.

As best seen in FIGURES 5 and 10, the bottom of the side support has a planar surface or guideway 130 which is perpendicular to the spindle plane PSA and oriented in the plane at a 60° acute angle to the spindle axis. It might be pointed out here that the key and keyway means 74 and 75 are set up so that lateral adjustment of a side support does not disturb this relationship.

Movably mounted on the guideway 130 is a housing 131 (see also FIGURE 2) and held in the guideway by gibbs 132 secured by bolts 133. The housing 131 is formed with an axial bore 135 which constitutes a cylinder for the piston 136. The piston rod 137 of the piston 136 is rigidly secured by screws 138 to an end block 139 which in turn is rigidly secured to the side support member by screws 140.

At the end of the housing or cylinder 131 toward the vertical center line of the machine an inclined surface 144 is provided against which the roller block 150 of the work roller R is secured by screws 151 and a positioning key 152. Suitable anti-friction bearings (not shown) are provided for rotatably mounting the roller R in the block 150. Each block mounts its roller so that the rotational axis of the roller makes an acute angle of 75° to the spindle axis.

The piston rod 137 (FIGURE 6) has a central passage 153 and lateral ports 154 communicating with the out-

board end of the cylinder and the inboard end of the cylinder is provided with ports 156 and 157. The ports 156, 157 and 155 (on the outboard end of the cylinder) are under control of the tracer valve SD mounted on the roller housing 131 by a bracket 158 secured thereto by screws 159 (FIGURES 2 and 4).

In general, when fluid is flowing into the outboard end of the cylinder and out of the inboard end of the cylinder, the roller rest is moving away from the spindle axis. When the fluid flow is reversed, the roller rest is moving toward the spindle axis.

The manner in which this fluid flow is controlled will be described hereinafter.

The construction above described is such that the rotational axis of the rollers, the axes of the cylinders 135 and pistons 136 all lie in the plane PSA. Further, the axes of the cylinders and pistons are parallel to the guideway and, therefore, are oriented at an acute angle of 60° with respect to the spindle axis. When a roller rest moves its roller during a working operation, the roller and/or its working tip or surface moves in said plane. The foregoing has several important advantages.

During a working operation the thrust of the roller is transmitted to the side support 70 through the roller block 150, cylinders 135, pistons 136 and end block 139. With the above-described construction, the resultant of this thrust lies in the plane PSA. Also, the resultant of the forces developed by the piston and cylinder for controlling the roller lie in the spindle plane. Thus, there are no forces or moments which develop which would tend to cause undesired carriage distortion and effect a tendency to move the roller out of the spindle plane nor to cause deviation of the relative desired position of the roller and the spindle during the working operation. This is highly important from the standpoint of the ability to produce accurately dimensioned articles.

Positioning the roller so that its axis lies at an acute angle of 75° with the spindle axis is important from the standpoint of ease of working the blank because the plane of the roller working tip is closely parallel (15°) to the direction in which the strata of the blank are displaced, i.e., generally parallel the spindle axis. Thus the necessary power to work the blank is reduced.

Orienting the path of the roller at an angle of 60° is important from the standpoint of machine construction, particularly in minimizing the overall length and width of the machine and in the use of components of relatively small size for the forces involved in the working operation. For example, when the carriage path and roller path are oriented at 90° to each other, the total lineal movement of the roller and carriage is a minimum for the purposes of placing a blank on the spindle, working the same, and then removing. In this type of an arrangement relatively large components are required as the resultant thrust of the rollers is at an acute angle to the spindle axis. By orienting the roller to move at an acute angle, generally smaller components can be used for the forces involved. By making this acute angle 60°, the total lineal movements of the rests and carriage are only slightly more than the 90° condition. While acute angles of less than 60° may be used, this has the disadvantage of requiring much longer carriage movement and hence a longer machine. Also, if acute angles of 45° or less are used, this requires substantially greater roller movement and hence a much wider machine.

Templet Mounting Structure

Patent 3,104,640 discloses an arrangement for automatically and correctly positioning the templet, hence the rollers, at the start of the working operation so that variations in blank thickness have no effect on the dimensional accuracy of the article or the object being formed. The present invention makes certain improvements in the structure for accomplishing the foregoing. Essentially this is done by providing a main support which is directly

mounted on the carriage and carrying both the templets and the tailstock. This main support is adapted to be positively moved in opposite directions by hydraulic means which also form a yielding connection with the carriage. The arrangement not only accomplishes the desired automatic compensation for deviation in blank thickness, but, in addition, provides several other highly useful advantages.

The arrangement has special advantage in connection with a vertical type machine of the kind described herein. With this vertical type machine it is not necessary for the tailstock to remain in contact with the formed article until the carriage, rollers, etc., have moved (usually the length of a blank) away from the spindle as is the case in a horizontal machine, as otherwise the article would fall off the spindle and be damaged or cause damage to the moving parts. On the vertical type machine it is only necessary that the tailstock remain in contact with the article until the spindle has been braked and its rotation has been stopped.

Thus, by mounting the templets and tailstock on a single structure supported on the carriage and having a yieldable connection therewith, several desirable objectives are accomplished. The templet and tailstock are a unitary structure and the templet is fixed in position for the working operation by the direct action of the tailstock contacting the blank. The yielding connection allows the templet to remain fixed during the working operation while the carriage moves, this yielding being provided by the hydraulic means. After the working operation the tailstock and templets are positively moved away from the spindle practically simultaneously with the carriage, this motion being provided by the yielding or hydraulic means.

Positively controlling the templets and tailstock so that the same move substantially simultaneously with the carriage back to the starting position has an additional important advantage in reducing the overall length of the machine. For example, it is necessary that the carriage, rollers, etc., when in the starting position, be spaced away from the tip of the spindle a distance at least the length of the largest article which the machine is capable of working. This, of course, is necessary in order that a worked article can be taken off the spindle. Also, it will be apparent that the yielding motion between the tailstock and templets and the carriage must be for a length which is at least twice the length of the largest article to be formed on the machine. Thus, in machines where the tailstock remains in contact with the blank after the working operation and is not positively moved back, for example its back motion being provided by engagement with the carriage, it is necessary for the carriage to travel back at least an additional length of the largest article to be made so that when the carriage is in starting position, the tailstock will also be in correct starting position. In other words, the total carriage travel has to be about three times the length of the largest article. By positively moving the tailstock back, the length of carriage travel may be reduced by one length of the article so that the overall length of the machine is shortened by that amount.

In FIGURE 2 the main support member is designated by 43. This is generally cylindrical in shape and is movably mounted in the aperture 76 of the central support block 68. The tailstock TS has a tailstock spindle 40 rotatably mounted by suitable anti-friction bearings in a housing 41 secured by bolts 42 to the support member 43. In addition to its function of positioning the templet, the tailstock assists in holding the blank on the spindle. The support member 43 has an upright extension 44 having a central bore 45 forming a cylinder for the piston 46. The piston is fixed to the head 77. The piston is double acting so that the support member can be driven up or down and so that the support member can remain fixed while the carriage moves. The axes of the piston and cylinder and the motion of the support

member are along the axis of the spindle and lie in the plane PSA. Thus, the thrusts on the tailstock during the working operation are along the spindle axis which is important from the standpoint of providing against off-axis loads and deflections. A bottom limit stop ring 49 is secured to the bottom of the block 68 to limit the extent of downward movement of the support 43.

Fluid may be admitted or exhausted to and from the upper end of cylinder 45 by side inlet pipe 118, lateral passage 119, annular chamber 120 and port 121. Fluid may be admitted or exhausted from and to the lower end of cylinder 45 by inlet pipe 123 and central passage 124. When fluid is flowing into the lower end and exhausting from the upper end, the support 43 is moving down. When fluid is flowing into the upper end and exhausting from the lower end, the support 43 is moving up. Also, this is the condition when the support 43 is fixed and the carriage, hence the piston 46, is moved down.

As seen in FIGURE 3, a laterally projecting arm 50 is secured to the support member 43 by means of a nut 51 and extends outwardly through the elongated slot 78 for connection to the templet slide 61, the connection (FIGURES 3 and 11) being made by means of an adjusting stud 53 and collars 54.

The templet slide 61 is mounted for up and down sliding movement in a vertically disposed gib plate 166 (FIGURES 4 and 7) which is rigidly secured by screws 167 to the front carriage side plate 66. This slide is connected to the laterally projecting arm 50 by the adjusting stud 53 as above described.

Mounted in the slide 61 for vertical adjustment in vertical kibs 168 are a pair of intermediate support members 169 and 170 having horizontally disposed gibs 171 (FIGURE 4) in which a pair of templet-carrying members 172 and 173 are adjustably mounted. The right-hand member 172 carries the right-hand templet and the left-hand member 173 carries the left-hand templet through the medium of arcuately adjustable plates 176 having depending mounting bars 177 to which the templets are secured by clamps 178.

It is to be observed that by reason of the adjustable mounting described, the templets are adapted for three adjustments for positioning them in proper relationship to the spindle. Adjusting knobs 179, 180 and 181 having, for example, suitable screw and nut connection with the intermediate support members 169 and 170, the templet-carrying members 172 and 173, and the arcuate plates 176, are provided to make the adjustments.

Thus, the templets can be independently adjusted up or down parallel to the center line of the tool by knobs 179, in or out at 90° to the center line by knobs 180 and angularly to line up the templet parallel to the tool by knobs 181. After the two templets have been properly positioned, the slide 61 can be adjusted up or down by the adjusting stud 53 to increase or decrease the distance between the rollers and the tool.

The Stripper Mechanism

The function of the stripper mechanism is to correctly support and align the blank with respect to the spindle at the start of the working operation and then to remove or strip the worked blank, or formed article, from the spindle after the working operation.

Referring particularly to FIGURES 1-3, 13-16, the stripper mechanism S comprises an annular plate 190 having a central clearance opening 191 for the spindle. The plate is arranged to reciprocate back and forth along the spindle axis. On the plate are radially disposed guideways 192 for receiving four adjustable stripper bars 193. The stripper bars 193 are adjusted inwardly to a position in which their inner portions 194 lap under the edge of the blank B, as shown in FIGURE 13 and are then clamped in place by tightening the gibs 195 by means of screws 196.

The stripper bars 193 have elongated shouldered slots

197 for receiving blocks 198 in which spring-loaded keepers 199 are pivoted at 200. The keepers 199 engage the periphery of the blank B to center it with respect to the spindle axis. The keepers are adjusted to proper centering position in the slots 197 and then are clamped in place by means of clamps 201 and screws 202.

The plate has two operating positions. In the upper position (FIGURES 14 and 17), the bars 193 support a blank mounted on the end or nose of the spindle and the keepers 199 centrally position the same. In the lower position (FIGURES 1-3, 18 and 19), the plate is held in readiness to move up and strip the formed cone 203 from the spindle.

In the upper position the top surfaces 194a (FIGURE 16) of the stripper bars lie flush with the end of the spindle in order to prevent buckling of the blank when the tailstock spindle 40 urges the blank tight against the spindle.

Up and down movement is imparted to the stripper plate by means of depending pistons 204, 204 carried by the plate 190 and operating in cylinders 205 mounted in the base 90. As best seen in FIGURES 3 and 14, spring-loaded cushioning stops 206, engageable with the top surface of the base, cushion the downward movement of the stripper plate. The manner in which fluid is supplied to the cylinders 205 for controlling the plate will presently appear.

The above-described operating positions of the spindle are for articles whose overall length is the same as the conical length 207 (see FIGURE 14) of the spindle. In such instances the diameter of the blank is made slightly larger than the diameter of the cylindrical part 208 of the spindle. This type of blank formed into an article will have a small shoulder 209 when the rollers (when working the blank) reach the juncture 210 between the conical and cylindrical parts of the spindle. The stripper bars are adjusted radially so that they will just clear the cylindrical part 208 in the down position. Upward movement of the plate after the working operation will cause the surfaces 194a to engage the shoulder 209 and remove the blank from the spindle. The keepers 199 will also engage the shoulder 209 and tend to support the blank for the stripping operation. In the up position, the bars will support the blanks as described heretofore.

When articles have a length less than the length 207, it is necessary that the down position of the stripper be closer to the top position, the exact location depending upon the length of the article. For this purpose, the stops 206 may be replaced by longer stops and the stripper bars 193 adjusted to the correct radial position. Such articles are formed with a shoulder so as to provide an engaging means for the stripper bars. The position of certain other control switches for the fluid supply to the cylinders 205 must be accordingly adjusted as will presently appear.

Machine Control Elements

The various control elements such as switches, trip dogs, relays, solenoids, valves and solenoid-operated valves used in the machine are of standard construction. The structure of such elements is well understood by those skilled in the art and, therefore, except in certain instances, the structural details will not be described.

The location of certain limit switches and their trip dogs is necessary for an understanding of the machine's operation and this is described below. These limit switches are fixed on various parts of the bed and the trip dogs are fixed on certain of the movable parts of the machine.

The slide 61 of the templet structure Te has secured thereto in spaced parallel relation, a right-hand upright bracket 220 and a left-hand bracket 221 (FIGURES 1, 2, 4, 17-19). The right-hand bracket 220 has a pair of vertically disposed rods 222 on which a pair of switch trip

dogs 1t, 2t are adjustably secured, and the left-hand bracket has similar rods 223 on which a pair of switch trip dogs 7t and 9t are adjustably secured. The depending brackets 95 are located adjacent the brackets 220 and 221 and each has a pair of vertically spaced limit switches mounted thereon. The limit switches 1LS and 2LS mounted on the right-hand bracket are actuated by the trip dogs 1t and 2t. The limit switches 7LS and 9LS mounted on the left-hand bracket are actuated by the trip dogs 7t and 9t.

The carriage C has an upright bracket 230 secured to its side plate 67 (FIGURES 2-4, 17-19) in which four vertically disposed spaced rods 231 are mounted. On these rods, reading from right to left in FIGURES 3 and 4, switch trip dogs 4t, 5t, 3t and 6t are adjustably secured. Mounted on the face of the right-hand upright brace member 92 of the machine framework are four limit switches 4LS, 5LS, 3LS and 6LS arranged in vertically spaced staggered relation (FIGURE 3) for actuation by the trip dogs 4t, 5t, 3t and 6t respectively.

The stripper plate 190 has a switch actuating arm 235 secured thereto and adapted to actuate a switch limit 8LS, mounted on the right-hand brace member 92, through the medium of an adjustable switch trip dog 8t and an adjustable trip block 236 secured on a vertical trip rod 237. The trip rod is mounted in blocks 238 secured to the brace member 92. It is to be observed that the trip brackets 220, 221 and 230 and their associated switches are diagrammatically illustrated in FIGURES 17, 18 and 19 to simplify the showing. The contacts of the limit switches 1LS, are also diagrammatically shown in FIGURE 22.

Switch 1LS has a single contact 1LS-1 normally opened, and closed momentarily as templet mounting structure Te moves down (by dog 1t on Te).

Switch 2LS has a single contact 2LS-1 normally opened, and closed momentarily as templet mounting structure Te moves down farther (by dog 2t on Te).

Switch 3LS has two contacts, 3LS-1 normally closed, and 3LS-2 normally opened, which are respectively opened and closed momentarily to stop the carriage C at the start of the working operation (by dog 3t on C).

Switch 4LS has two contacts, 4LS-1 normally closed, and 4LS-2 normally opened, which are respectively opened and closed momentarily to stop the carriage C at the end of the working operation (by dog 4t on C).

Switch 5LS has two contacts, 5LS-1 normally closed, and 5LS-2 normally opened, which are respectively opened and closed as the carriage C moves up after the working operation (by dog 5t on C).

Switch 9LS has a single contact 9LS-1 normally opened, and closed momentarily as templet mounting structure Te moves up after the working operation (by dog 9t on Te).

Switch 7LS has a single contact 7LS-1 normally closed, when the templet mounting structure is in its up position (by dog 7t on Te).

Switch 8LS has a single contact 8LS-1 normally opened when the stripper is in the up position (by dog 8t on S).

Switch 6LS has a single contact 6LS-1 normally closed which is opened when the carriage C is in its up position (by dog 6t on C).

Certain selector switches are used in the control system. These are preferably the rotary type. The general function of these selector switches is explained, particularly in connection with FIGURE 22. On the left-hand side of FIGURE 22 there is a scale being numbered (23)-(41). In the description below, to find the selector switch mentioned, look to the right of the particular identifying number.

70 Selector Switch 2-SS (24).—This has "on" and "off" positions for controlling the starter 2m controlling the motor operating the pump for various hydraulic circuits.

Selector Switch 3-SS (25).—This switch has "on" and "off" positions and is used for conditioning the machine for operation.

Selector Switch 4-SS (26).—This switch has "up," "down" and "off" positions and is used for independently controlling the templet mounting structure.

Selector Switch 5-SS (30).—This switch has "down," "off" and "up" positions and is also used for independently controlling the templet mounting structure.

Selector Switch 6-SS (33).—This switch has "up," "off" and "down" positions and is for use in independently controlling the carriage.

Selector Switch 7-SS (35).—This switch has "run," "off" and "brake" positions and is for independently controlling the spindle.

Selector Switch 8-SS (38).—This switch has "out" and "in" positions and is used for independently controlling the rollers rests.

Selector Switch 9-SS (40).—This switch has "up," "off" and "down" positions and is for independently controlling the stripper.

Certain other switches and components will be briefly described with further reference to FIGURES 21 and 22.

In FIGURE 21 the disconnect switch DS (2) is adapted to energize and de-energize the three-phase main supply lines L-1, L-2 and L-3 (3). As shown, these lines supply power to the spindle motor M (3) and the hydraulic pump motor M-1 (4) through the overload devices generally designated as OL and the starter contacts 1m-1 and 2m-1. The lines L-1 and L-2 supply power to a transformer 250 which is for supplying power to the various solenoids Sol-1, sol-2, etc. The lines L-1 and L-2 feed the lines 1-1 and 1-2 supplying power to the circuits shown in FIGURE 22. The transformer 250 is connected to a transformer 251 (18) supplying power to a rectifier 252 (19) which serves as a supply for the solenoids Sol-12 and Sol-13 (20) and (21).

In FIGURE 22 the master stop switch MS (23) is for use in stopping the machine in the event of an emergency. The machine start CS (23) is for use in energizing the spindle motor M, starter 1m and the hydraulic pump motor starter 2m (24). Note that the spindle motor starter 1m is fed through the overload contacts OL-1 (23) and that the pump motor starter 2m is fed through the spindle motor starter contacts 1m-2 (24). Also in FIGURE 22, the manually operated switch 253 (32) is for use in independently controlling the roller rests. When the machine is operating automatically, the switch is in the position shown.

The relays used in the control system are of standard construction and are shown diagrammatically in FIGURE 22. The designations of these relays all include the letters CR or TR, for example, the relay 5CRA (25), the relay 1CR (27), the relay 3TR (34), etc. All of these relays, except 5CRA and 3TR, when de-energized, have contacts which are open and, when energized, the contacts close. The contacts of the 5CRA and 3TR relays are closed when these relays are de-energized. The manner in which the relays are controlled and the functions they initiate will be explained hereinafter.

The solenoids used in the control system are of standard construction and are diagrammatically shown in FIGURES 20a and 21. The designations of the solenoids include the letters Sol, for example, in FIGURE 21, Sol-1, Sol-2, etc. These solenoids operate certain control valves diagrammatically represented in FIGURE 20 as V-1, V-2, etc. These valves are of standard construction. The manner in which the solenoids are energized and de-energized to control the valves together with the manner in which the valves function, will be explained later.

Machine Operation

The operation of the machine will be described particularly with reference to FIGURES 17-22.

FIGURE 17 shows the relationship of certain of the components when the machine is in the standby or start position. The carriage C and the templet mounting structure are all the way up and the roller rests are at their farthest outward positions. The spindle is non-rotating

and the stripper is in its up position. In this position it is assumed that the disconnect switch DS in FIGURE 21 (21) is closed so that the lines L-1, L-2 and L-3 (3), together with the transformer 250 (5) and 251 (18) and the lines 1-1 and 1-2, become energized. Also, in FIGURE 22 it is assumed that the hydraulic switch 2-SS (24) is in the "on" position. For automatic operation, the switch 3-SS (25) must be in the "on" position and all of the selector switches 4-SS-9-SS must be in the "off" positions.

The manner in which the carriage templet structure and the roller rests are held in the start position, the manner in which the spindle is in a non-rotating condition and the manner in which the stripper is held in the up position will also be more readily apparent hereinafter.

Further, it is assumed that the machine start switch CS (23) is closed to energize the spindle starter 1m which closes the contacts 1m-1, FIGURE 21 (3), to start the rotation of the spindle motor M. Also in FIGURE 22 (24), the contacts 1m-2 close to energize hydraulic motor starter 2m, which closes the contacts 2m-1, FIGURE 21 (4), to energize the hydraulic pump motor M-1.

It will be recalled from the above description that the contacts 1m-2 (24) are closed and the switches 2-SS (24) and 3-SS (25) are both "on." This energizes the relays 5CRA, 5CRB and 5CRC. Energizing of the 5CRA relay opens all of the contacts 5CRA-1 through 5CRA-6 which are in the normally closed position. Energizing of the 5CRB relay closes all of the 5CRB-1 through 5CRB-6 contacts which are normally open. The same is true for the contacts 5CRC-1 through 5CRC-3.

A blank is loaded in the stripper as heretofore described. To start operation, the cycle start switch 10-SS (27) is closed and this energizes the relay 1CR. Energizing of the relay 1CR closes all of its normally open contacts 1CR-1 through 1CR-4. The relay is held up through its contacts 1CR-1 (27).

Referring to FIGURE 22, the 1CR-2 contacts (29) energize the 3CR relay so that each of its normally open contacts 3CR-1 and 3CR-2 close. Referring to FIGURE 21 (7), the 1CR-3 and 1CR-4 contacts energize the solenoid Sol-1. With the 3CR relay energized, the 3CR-1 and the 3CR-2 contacts, FIGURE 21 (9), energize the solenoid Sol-3.

Templet Mounting Structure Down

Referring to FIGURES 20 and 20a, the energizing of solenoids Sol-1 and Sol-3 cause the templet mounting structure to start to move down. This is explained following.

The pump 255 feeds a line 256 connected by a line 257 to the valve V-1 and also feeds a line 260 connected to the valve V-2. The energizing of the solenoid Sol-3 operates the valve V-2 to permit transfer of fluid between lines 260 and 261. The energizing of the solenoid Sol-1 operates the valve V-1 to permit transfer of fluid between lines 257 and 263. Referring back to valve V-2, the line 261 leads to a pipe 118 (FIGURE 20a) leading to the upper end of the cylinder 45 of the templet mounting structure Te. Referring to valve V-1, the line 263 is connected to valve V-3 which permits transfer of fluid between lines 264 and 265. The line 265 is connected to pipe 123 (FIGURE 20a) of the templet cylinder 45 leading to the lower end of the cylinder. It will be noted that the unit pressure on both sides of the tailstock piston 46 is the same; however, the differential area of the piston causes the templet support to move down with fluid flowing into the lower end of the cylinder and out of the upper end, which latter fluid goes through line 261, valve V-2, line 260 and joins with the fluid in line 257.

As the templet support structure moves down, the dog 1f momentarily closes the limit switch 1LS which, as seen in FIGURE 22 (31), energizes the relay 7CR. The relay's normally open contacts 7CR-1 and 7CR-3 close. The 7CR-1 contacts (31) hold up the relay. In FIGURE 21, the 7CR-2 and 7CR-3 contacts (13) energize the

15

solenoid Sol-7. Referring to FIGURES 20 and 20a, the energizing of solenoid Sol-7 causes the carriage to start down. This is explained following.

Carriage Moves Down

The pump 266 feeds a line 270 connected by a line 271 to the valve V-4 and by a line 272 to the valve V-5. The valve V-4 does not at this time transfer fluid from line 271. The valve V-5 permits the transfer of fluid between lines 272 and 273 which run to the valve V-6 which is operated by the solenoid Sol-7 as explained following.

The line 273 is connected to a line 274 connected to a line 275 running between the valves V-7 and V-8. The energizing of the solenoid Sol-7 operates the valve V-7 so as to transfer fluid from line 275 to line 280. The line 280 is connected to the control device 281. Before going on, the device 281 will be explained. This comprises a piston and cylinder as shown, the piston being normally held centrally of the cylinder by a spring when the unit pressure on opposite sides of the piston are the same. Previous to the operation of the solenoid Sol-7 and valve V-7, the left and right-hand sides of the device 281 were connected to drain. The right side was connected to drain via the line 282, the valve V-8, line 283, line 284 which is connected to a line 285 running to sump. The left side of the device 281 was connected to drain via the line 280, the valve V-7 and the line 284.

Continuing on, the operation of solenoid Sol-7 and valve V-7 causes fluid to transfer from the lines 274 and 275 through the valve V-7 to the line 280 to the left side of the piston device 281. The right side is connected to drain as explained above. The device 281 then operates valve V-6 to permit transfer of fluid between lines 273 and 286. The line 286 runs to pipes 115 (FIGURE 20a) leading to the top of the carriage cylinders. With fluid flowing to the bottom of cylinders 100 and out of the top of the cylinders, the carriage is moved down.

Both the carriage and the templet mounting structure are now moving down and as the templet mounting structure moves down farther, the dog 2t momentarily trips the limit switch 2LS so that the contacts 2LS-1 which, as seen in FIGURE 22 (37), energize the relay 9CR. The relay's normally open contacts 9CR-1 through 9CR-3 close. The 9CR-1 contacts (37) hold up the 45 relay. Referring to FIGURE 21, the 9CR-2 and 9CR-3 contacts (15) energize the solenoids Sol-9 and Sol-15.

Roller Rests In

Referring to FIGURE 20a, the energizing of the solenoids Sol-9 and Sol-15 cause the roller rests to move in or toward the spindle axis. This is explained following.

As mentioned heretofore, the structure and operation of the tracer mechanisms operating both roller rests are the same and the following explanation will be only in connection with the right-hand roller rest.

The valve V-9 operated by the solenoid Sol-9 together with the tracer valve SD cooperate to transfer fluid as between the inboard and outboard ends of the templet cylinder 135 so as to cause the cylinder to move in or out. When the solenoid Sol-9 is de-energized, the valve V-9 and the tracer valve SD cooperate to cause the cylinder to move out, which is its position as shown in FIGURE 20a. When the solenoid Sol-9 is energized, the valve V-9 and the tracer valve SD cooperate so that the cylinder movements are under the control of the tracer stylus 290. As is the usual case with tracer valves, the stylus, in contacting the templet, causes whatever is connected to the valve (in this case the roller rest cylinder 135) to oscillate back and forth, the oscillation being so small that the cylinder occupies positions as dictated by the shape of the templet. The roller being connected to the cylinder has its transverse motion controlled by the tracer valve and templet.

Referring to FIGURE 20, the pump 291 feeds a line

75

16

292 connected to the ports 153 and 154 supplying fluid to the outboard end of the roller rest cylinder 135.

With the solenoid Sol-9 energized, the valve V-9 is actuated so that fluid flows through the port 155, line 294, valve V-9, line 295 through the tracer valve SD to the line 296 through the relief valve 300, the line 301 and port 157 to the inboard end of the cylinder 135. When the cylinder has moved in to uncover the port 156, fluid from the line 296 goes through the line 302 and port 156. It will be apparent that the same unit pressure exists on the inboard and outboard sides of the piston. However, the differential area causes the cylinder to move in. The cylinder 136 moves in until the stylus 290 contacts the templet. The tracer valve then shuts off the flow from line 295 to 296 and puts both the lines 295 and 296 in communication with drain line 303 connected to a line 304 running to sump. Thus, the inboard end of the cylinder has no fluid flowing into the same and with flow continuing into the outboard end, the cylinder moves out. Fluid is exhausted from the inboard end via lines 302 and 296 and also through the line 305 and check valve 306 connected to line 295 which is now connected to drain. As the stylus 290 leaves the templet, the tracer valve operates to move the cylinder in as described above. When the stylus again contacts the templet, the cylinder moves out. This back and forth motion is very small so that, for all practical purposes, the roller rest remains stationary.

When the solenoid Sol-9 is de-energized, the roller rest cylinder 135 is moved out as follows. The inboard end of the cylinder is connected to drain through port 156, line 302, line 296, tracer valve SD, line 295, valve V-9 and line 310 connected to drain line 304. On the outboard side, the fluid from said line 292 continues to flow through the ports 153 and 154 until the cylinder is all the way back. This is because the outboard side of the cylinder is connected by port 155, line 294 to valve V-9 which dead-ends the line 294.

Returning now to the sequence of operation, we have both the carriage and the templet mounting structure moving down and the roller rests moving inwardly. The templet mounting structure continues to move down until the tailstock contacts the blank and holds the same firm against the spindle and stripper bars when the stripper bars are set flush. The roller rests continue to move inwardly until their styls contact the templets and then the motion of the rests is stopped as discussed above. As the carriage continues to move down, the dog 3t momentarily trips the limit switch 3LS.

Referring to FIGURE 22 (31) the 3LS-1 contacts open to de-energize the relay 7CR. The 3LS-2 contacts (39) close to energize the 10CR relay (39).

The de-energizing of the 7CR relay opens its contacts 7CR-1 to 7CR-3 which has the following effect. The 7CR-1 contacts (31) are opened so as to maintain the relay 7CR de-energized. The 7CR-2 and 7CR-3 contacts, FIGURE 21 (13), open to de-energize the solenoid Sol-7 which acts to stop the carriage motion as explained following.

Carriage Stops

With reference to FIGURE 20, it will be recalled that the line 273 from the carriage pump 266 is feeding the top of the carriage cylinders 100 through valve V-6. When the solenoid Sol-7 is de-energized, the valve V-7 stops the fluid flow from the lines 274 and 275 to the left side of the control device 281 and connects the same to drain via the line 280, valve V-7 and line 284 connected to the drain line 285. The right side of the control device 281 is connected to drain via the line 282, valve V-8, line 283, line 284 connected to drain line 285. Thus, the piston of the control device 281 returns to the normal center position as shown, by the action of a spring associated with the valve V-6. The

valve V-6 opens the fluid connection between the feed line 273 and the line 286 and connects line 286 to drain line 285. The line 290 is also connected to drain line 285.

With no fluid flow to the carriage cylinders, the carriage stops moving. The carriage is held in position by the counter-weight CW. It is to be noted that the limit switch 3LS which initiates the carriage stop is set so that the carriage positions the rollers just above but not in contact with the blank.

The energizing of the relay 10CR causes its normally open contacts 10CR-1 to 10CR-4 to open. The 10CR-1 contacts (38) close to energize the relay 1TR, the effect of which will be explained later. The 10CR-2 contacts (39) hold up the relay. With reference to FIGURE 21, the 10CR-3 and 10CR-4 contacts (16) energize the solenoid Sol-10 which causes the stripper to move down. This is explained following.

Stripper Down

With reference to FIGURE 20, it will be recalled that the pump 266 feeds the line 271 via the line 270, the line 271 being connected to the valve V-4. When solenoid Sol-10 is energized, it actuated the valve V-4 to connect line 271 to line 310 and line 310 to line 312 which is connected to the drain line 285. With reference to FIGURE 20a, it will be seen that the line 310 feeds the lines 313 and 314 connected to the top end of the stripper cylinders 205 and that the line 311 is connected to the lines 315 and 316 connected to the bottom end of the cylinders 205. With fluid flowing into the top of the cylinders 205 and draining from the bottom, the stripper moves to its down position. The blank remains in engagement with the spindle by the action of the tailstock.

Spindle Rotates

The energizing of the 10CR relay as mentioned above causes the spindle to rotate. This is explained following. With reference to FIGURE 22 (38), it will be recalled that the 10CR-1 contacts energize the 1TR relay and its normally open contacts 1TR-1 and 1TR-2 close. The 1TR-2 contacts (38) hold up the relay. The 1TR-1 contacts (36) are connected to a time-delay mechanism as indicated, so that they do not close instantaneously and, after a brief interval, the 1TR-1 contacts energize the relay 12CR. The energizing of the 12CR relay closes its normally open contacts 12CR-1 to 12CR-3. The 12CR-1 contacts hold up the relay and also energize the 2TR relay. With reference to FIGURE 21 (21) the contacts 12CR-2 and 12CR-3 energize the solenoid Sol-12 which operates to actuate the spindle clutch 33, which interconnects the spindle with the main drive motor M, the spindle and blank start rotating.

As mentioned just above, the 12CR-1 contacts energize the 2TR relay which has normally open TR-1 contacts. The 2TR-1 (32) contacts are connected to a time-delay mechanism as indicated so that they do not close instantaneously. After a brief delay the 2TR-1 contacts close to energize relay 6CR. The normally open contacts 6CR-1 to 6CR-3 close. The 6CR-1 contacts (32) energize the relay 7CR.

Thus, both the relays 6CR and 7CR are energized and the effect of this is to start the carriage down again as will be explained below.

Carriage Moves in Working Operation

In FIGURE 21 (12) the 6CR-2 and 6CR-3 contacts energize the solenoid Sol-6 which, as seen in FIGURE 20, controls the valve V-11 which controls the valve V-5. The valve V-5 causes fluid for the carriage cylinder to flow through a rate control 320. The rate control is of standard construction comprising a variable orifice 321 and relief valve 322 connected to the line 323 running to sump. The orifice may be varied so that the carriage can be moved down at a predetermined rate.

It will be recalled that the carriage pump 266 feeds the line 272 which is connected to a line 324 running to the valve V-11. When activated by the energized solenoid Sol-6, the valve V-11 transfers fluid from the line 324 to a line 325 connected to control device 326 which operates the valve V-5. The control device 326 is like the control device 281.

Normally the piston of the control device 326 is centered as shown by the action of a spring associated with valve V-5 because the cylinders on both sides of the piston have the same unit pressure. This is the case when the solenoid Sol-6 is de-energized and is done as follows. The line 330 is connected to a line 331 which is connected to the right side of the cylinder and this line 330 is also connected via the valve V-11 to line 325 running to the left side of the cylinder. The line 330 is connected via the valve V-5 to a line 332 running to the input side of the rate control 320. The output line 333 of the rate control is connected to the feed line 273.

Returning now to the operation of solenoid Sol-6 and valve V-11, it will be recalled that the energizing of solenoid-operated valve V-11 to transfer fluid from the line 272 to the line 325 running to the left side of the device 326 so that the piston moves to the right and activates the valve V-5. The right side of the control device is exhausted through lines 331 and 330 and line 332. Valve V-5 then connects the line 272 to line 332 and fluid flows through this line through the rate control 320 out through line 333 back to line 273 connected to valve V-6.

It will be recalled that the operation of the relay 6CR energized the relay 7CR which acts as explained above, i.e., to energize solenoid Sol-7 which operates valve V-7, control device 281 and valve V-6 so that the line 273 is in communication with the line 286 connected to the bottom of the carriage cylinders. The valve V-6 also contacts the line 290 connected to the top of the carriage cylinders to the drain line 285.

Thus, fluid flows into the carriage cylinders in a manner to move the carriage down, the flow being controlled by the rate device 320.

It will be recalled that the carriage had been stopped so that the rollers were a short distance away from the blank and, therefore, not in contact with the same. At this time the rollers occupy radial positions with respect to the spindle axis which are shorter than the correct radial distances for the working operation. As the carriage moves the rollers down, the templets, being fixed in position (in accordance with the thickness of the blank) cause the rollers to move outwardly so that at the time the rollers contact the blank, they are at the correct radial distances from the spindle axis. The templets, of course, are initially set up for accomplishing the foregoing.

As the carriage continues to move down, the rollers work the blank over the spindle. The carriage provides a component of roller motion along the spindle axis and each roller rest provides its roller with a component of motion transverse the axis, the latter motions being under the control of the tracer mechanisms. Thus, the rollers are maintained the correct distances from the spindle surface (or spindle axis) so that the desired article, thickness and/or contour is obtained.

The required yielding connection between the carriage and the templet mounting structure (so the carriage can move down as the templet remains fixed) is provided by the templet mounting structure, pistons and cylinders as follows. In the templet structure it will be recalled that the piston 46 is connected to the carriage and as the piston moves down with the carriage into the cylinder 45, the fluid in the lower part of the cylinder flows out the pipe 123 (FIGURE 20a), the line 265, line 264 (FIGURE 20), valve V-3, line 263, valve V-1 and line 257 and joins with the fluid in the line 260 which is flowing up through the valve V-2 to line 261 connected to the pipe 118 leading to the top of the cylinder 46.

The carriage continues to move downwardly to a point consistent with the length of the article to be formed. In

this case the carriage moves down until the rollers have been moved to the point 210 as shown in FIGURE 18, i.e., the juncture between the conical and cylindrical parts of the spindle. For stopping the machine at this point the dog 4t is set up to activate the 4LS switch. The 4LS switch initiates several functions. With reference to FIGURE 22, the 4LS-1 contacts (31) open to de-energize the relay 7CR, the relay 6CR (32), the relay 12CR (36), the relay 2TR, the relay 9CR (37) and the relay 1TR (39). Also, the 4LS-2 contacts (34) close to energize the relay 8CR. The effect of the operation of these relays causes the carriage to stop, the roller rests to move all the way out and for the spindle clutch to be de-energized, the carriage to move up and the spindle brake to be applied. The manner in which the foregoing is accomplished is explained below.

Carriage Stops

When the relay 6CR is de-energized, the contacts 6CR-1 to 6CR-3 open. In FIGURE 22 (32), the 6CR-1 contacts are open so that the relay 7CR cannot be held up. In FIGURE 21 (12), the 6CR-2 and 6CR-3 contacts open to de-energize the solenoid Sol-6. In FIGURE 20 the solenoid Sol-6 causes the valve V-11, the control device 326 and valve V-5 to function as described heretofore. The valve V-5 cuts off the flow of fluid from the carriage feed line 272 to the rate control line 332 and connects the line 272 to the line 272 running to the valve V-6.

When the relay 7CR is de-energized, the contacts 7CR-1 to 7CR-3 open. In FIGURE 22 (31) the 7CR-1 contacts open so that the relay 7CR cannot be held up. In FIGURE 21 (13), the 7CR-2 and 7CR-3 contacts de-energize the solenoid Sol-7. In FIGURE 20 the solenoid Sol-7 being de-energized, causes the valve V-7, control device 281 and valve V-6 to function as described heretofore. The valve V-6 does not permit flow of fluid from the carriage feed line 273 to the line 286. Instead, the line 286 and line 290 are connected to the drain line 285. Thus, with no fluid flowing to the carriage cylinders, the carriage stops.

Roller Rests Move Out

In FIGURE 22 the 9CR relay (37) being de-energized, opens its contacts 9CR-1 to 9CR-3. The 9CR-1 contacts (37) prevent the relay from being held up. In FIGURE 21 (15) the 9CR-2 and 9CR-3 contacts de-energize the solenoids Sol-9 and Sol-15. As explained in connection with FIGURE 20a, when the solenoid Sol-9 is de-energized, it activates the valve V-9 which, in cooperation with the tracer valve SD, functions to move the right roller rest outwardly. The solenoid Sol-15 and valve V-12 function and move the left-hand roller rest in the same manner.

Spindle Clutch De-energized

In FIGURE 22 the 12CR relay (36) being de-energized, opens its contacts 12CR-1 to 12CR-3. The 12CR-1 contacts (36) open to de-energize the relay 2TR so that the 2TR-1 contacts (32) open after a short delay. In FIGURE 21 (20) the 12CR-2 and 12CR-3 contacts de-energize the solenoid Sol-12 which operates to de-energize the spindle clutch 33 so that the spindle is disconnected from the main drive motor M.

Carriage Moves Up

In FIGURE 22 the 8CR relay (34) being energized, causes the normally open contacts 8CR-1 to 8CR-4 to close. The 8CR-1 contacts (34) hold up the relay and also energize the 3TR relay. The 3TR-1 contacts (35) are ready to open, being held in position momentarily by a time-delay device connected thereto. The 8CR-2 contacts (34) close to energize the relay 13CR. In FIGURE 21 the 8CR-3 and 8CR-4 contacts (14) close to energize the solenoid Sol-8.

The energizing of the solenoid Sol-8 causes the carriage to move up as explained below. With reference 75

to FIGURE 20, the solenoid Sol-8 actuates the valve V-8. The valve V-8 interconnects the line 275 (which is connected to the carriage feed line 273) to the line 282 connected to the right side of the control device 281. The control device 281 operates the valve V-6 so that the carriage feed line 273 is connected to the line 290 and the line 286 is connected to the drain line 285. Thus, it will be seen that the direction of fluid flow to the carriage cylinders is reversed. The carriage, therefore, moves up.

As mentioned above, the relays 3TR and 13CR are energized. These function to brake the spindle to stop its rotation as explained below.

Spindle Brake

When the relay 13CR is energized, its normally open contacts 13CR-1 and 13CR-2, FIGURE 21 (21), close to energize the solenoid Sol-13. The solenoid Sol-13 causes the brake 34 to operate to stop the rotation of the spindle. The brake is applied a sufficient time to stop the spindle, this time being controlled by the contacts 3TR-1 (34). When these contacts have opened, the relay 13CR is de-energized which de-activates the brake.

Templet Mounting Structure Goes Up

After the carriage has moved up a short distance, the dog 5t momentarily actuates the 5LS switch. In FIGURE 22, the 5LS-1 contacts (27) open to de-energize the relay 1CR and its contacts open. The holding contacts 1CR-1 open so that the relay is not energized when the 5LS-1 contacts are closed again. The 5LS-2 contacts (28) momentarily close to energize the relay 2CR. The relay is held up by the contacts 2CR-1. Also, the 2CR-2 contacts (29) close to maintain the relay 3CR energized despite the fact that the 1CR-2 contacts have opened.

In FIGURE 21 the contacts 1CR-3 and 1CR-4 (7) de-energize the solenoid Sol-1. The contacts 2CR-3 and 2CR-4 (8) energize the solenoid 2. Also, the 3CR-1 and 3CR-2 (9) maintain the solenoid Sol-3 energized.

In FIGURE 20a the line 265 (which is connected to the bottom of the templet cylinder 45) is connected (FIGURE 20) to the valve V-1 via the line 264, valve V-3 and line 263. With the solenoid Sol-1 de-energized and solenoid Sol-2 energized, the line 263 is connected to drain line 340 which is interconnected to the line 341 running to sump. Thus, the bottom of the templet cylinder is connected to drain. Also, FIGURE 20, the line 261 (which is connected to the top of the templet cylinder 45) is directly connected to the valve V-2. With the solenoid Sol-3 energized, the valve V-2 interconnects the line 261 to the line 260 which runs back to the pump 255. With the connections described, the templet mounting structure begins to move up.

The templet structure continues to move up until the dog 9t momentarily actuates the switch 9LS. The operation of the switch 9LS actuates certain of the controls so that the stripper mechanism moves up. This will be explained following.

Stripper Moves Up

In FIGURE 22 the contacts 9LS-1 (41) momentarily close. The 8LS-1 contacts (41) are at this time closed, since the stripper is not all the way up. Thus, the relay 11CR is energized. The 11CR-1 contacts close to hold up the relay when the 9LS-1 contacts open. In FIGURE 21 (17) the 11CR-2 and 11CR-3 contacts close to energize the solenoid Sol-11. In FIGURE 22 the 11CR-4 contacts open to de-energize the relay 10CR and open the contacts 10CR-1 to 10CR-4. The 10CR-3 and 10CR-4 contacts de-energize the solenoid Sol-10 which allows the solenoid Sol-11 to control the valve V-4.

In FIGURE 20 the solenoid Sol-11 operates the valve V-4 so that the line 271 connected to the pump 266 is connected to the line 311. The valve also connects

the line 310 to the drain line 312. With reference to FIGURE 20a it will be seen that line 311 conducts fluid to the bottom of the cylinders 205 and the line 310 is interconnected to the top of the cylinder 205. Thus, with fluid flowing into the bottom and out the top the stripper starts to move up.

As explained heretofore, as the stripper moves up, it engages the formed article and starts to move the same off the spindle.

Templet Mounting Structure Stops

When the templet mounting structure has returned to its desired uppermost position in the carriage, the switch 7LS is tripped. In FIGURE 22 the contacts 7LS-1 (28) open to de-energize the relay 2CR. The holding contacts 2CR-1 open and the contacts 2CR-2 (29) open to de-energize the relay 3CR. In FIGURE 22 (8) the 2CR-3 and 2CR-4 contacts open to de-energize solenoid Sol-2. Also, the contacts 3CR-1 and 3CR-2 open to de-energize the solenoid Sol-3.

In FIGURE 20 the solenoid Sol-3 operates the valve V-2 so fluid flowing from the feed line 260 through the valve V-2 to the line 261 is stopped. The line 261 is connected to the top end of the templet mounting structure cylinder so that no fluid flows to the same. Also, the solenoid Sol-2 operates the valve V-1 so that fluid flowing from the feed line 257 through the valve V-1 to the line 263 is stopped. The line 263 is interconnected to the bottom of the templet mounting structure cylinders so that no fluid flows to the same. The lines 261 and 263 are dead-ended by the respective valves. Thus, the movement of the templet mounting structure is stopped and the same remains fixed in position.

Carriage Stops

As the carriage continues to move up, it reaches its desired uppermost position and the dog 67 trips the switch 6LS. In FIGURE 22 (34), the 6LS-1 contacts open to de-energize relay 8CR and relay 3TR. The contacts 3TR-1 are closed. The 8CR-1 to 8CR-4 contacts open. The 8CR-1 and 8CR-2 holding contacts open. In FIGURE 21 the 8CR-3 and 8CR-4 contacts (14) open to de-energize the solenoid Sol-8. In FIGURE 20 the solenoid Sol-8 operates the valve V-8 to cut off the flow of fluid in line 282 to the right side of the cylinder device 281 so that its piston moves to its center position and the valve V-6 causes the lines 290 and 286 to both be connected to drain line 285. With no fluid flowing into the carriage cylinders, the carriage stops being maintained in position by the counter-weight CW.

Stripper Stops

When the stripper has moved to its required up position, the switch 8LS is opened. In FIGURE 22 (41) the contacts 8LS-1 open to de-energize the relay 11CR. The 11CR-1 holding contacts (41) open. In FIGURE 21 the contacts 11CR-2 and 11CR-3 (17) open to de-energize the solenoid Sol-11. In FIGURE 20 the solenoid Sol-11 actuates the valve V-4 so that the line 311 and the line 310 are dead-ended so that fluid flowing from the feed line 271 through the valve to the line 311 and exhaust fluid flowing in the line 311 through the valve to the drain line 312 is stopped. Thus, with the fluid supply to the stripper cylinders cut off, the same stop and remain in the stop position. The 11CR-4 contacts close to set up the relay 10CR for subsequent operations.

The machine is now in the starting or standby position. The formed article can be removed from the stripper either manually or automatically and a new blank inserted. By closing the cycle start switch 10-SS the machine will operate as described above.

Non-Automatic Operation

The control system for the machine is arranged so that the carriage, templet mounting structure, roller rests, stripper and spindle can be operated independently of each

other. This is accomplished by the medium of the selector switches 4-SS to 9SS and by turning the selector switch 3-SS to the "off" position.

For example, if it is desired that the templet mounting structure be moved down, the selector switch 4-SS is moved to its "down" position which interconnects the line 350 to the line 351 so as to energize the relay 1CR. The energizing of the relay 1CR causes functioning of the system as heretofore described so as to move the templet mounting structure down. If the templet mounting structure is to be moved up, then the selector switch is moved to the "up" position which interconnects the line 352 to the line 353 to energize the 2CR relay. The 2CR relay causes operation of the control system as heretofore described for moving the templet mounting structure up.

The manner in which the other components of the machine may be independently operated by the operation of the selector switches will be apparent from the description and need not be discussed in detail.

Templet Mounting Structure as a Press

In certain instances it is desired to use the templet mounting structure as a press to push or pull work off the spindle, especially when the spindle and work are cylindrical in shape. When used to push articles on the spindle, the rate at which the templet mounting structure moves downwardly is controlled through a rate control device. The manner in which the foregoing is done will be explained following.

For moving the templet mounting structure down, the switch 5-SS is turned to the "down" position. Switch 5-SS connects line 354 to line 355 to energize the relay 4CR. The 4CR-5 contact (27) closes to energize the 1CR relay. The energizing of the 1CR relay causes energizing of the solenoid Sol-1. The energizing of the relay 4CR causes energizing of the solenoids Sol-4, Sol-5 and Sol-16, as will be seen from an inspection of FIGURE 21 (10).

In FIGURE 20 the solenoid Sol-1 operates the valve V-1 which connects the feed line 257 to the line 263. The solenoid Sol-4 operates the valve V-2 to connect the line 260 to the line 261. The solenoid Sol-5 operates the valve V-13 which disconnects the line 263a from the relief valve V-14 so that maximum flow or pressure can be obtained. The solenoid Sol-16 operates the valve V-3 to connect the line 263 with the line 360 going to the rate control 361. The rate control 361 is the same as the rate control 320. The fluid leaves the rate control via the line 362 which is connected to the line 265 going to the bottom of the templet mounting structure cylinder. Thus, flow to the bottom of the cylinder is controlled by the rate control device 361.

When the tailstock is to be moved up, the switch 5-SS is moved to the "up" position which connects lines 354 and 353 to energize the relay 2CR and de-energize the relay 4CR. The relay 2CR causes the system to operate as heretofore described to move the templet mounting structure up.

Summary of Operation

An overall understanding of the functioning of the machine in automatic operation can be readily followed from the chart of FIGURE 23 in which the time movements of the components are identified by a series of concentric circles. The outer circle represents the templet mounting structure, the next inner circle the carriage, the next inner circle the roller rests, the next inner circle the stripper and the innermost circle the spindle.

Assuming first that the carriage and templet mounting structures are stopped in their up positions, the roller rests are all the way out (the styls of the tracer valve being disengaged from the templets), the spindle is non-rotating and the stripper is in its up position and a blank is loaded in the stripper. The operator now pushes the cycle start button and, with reference to the chart, operational sequence in a cycle of operation is as follows.

- (a) The templet mounting structure starts down.
- (b) The carriage starts downward with the templet structure.
- (c) The roller rests start to move inwardly toward the spindle axis.
- (d) The tailstock of the templet mounting structure engages the blank against the tool so that the templet structure stops and the templets are positioned, the roller rests have moved in and are stopped by the styli of the tracer valves engaging the templet.
- (e) The carriage continues to move down until it is stopped with the rollers spaced from the blank.
- (f) The stripper starts to move downwardly.
- (g) The spindle clutch is engaged to start rotation of the spindle, the blank and the tailstock spindle.
- (h) After a slight time delay, the carriage moves down at a predetermined feed rate to start working the blank.
- (i) The stripper stops in its lowermost position.
- (j) When the article is completely formed, the carriage movement is stopped; the spindle clutch is disengaged; the carriage starts to move up; the roller rests start to move outwardly.
- (k) The spindle brake is momentarily applied to stop rotation of the spindle and formed article.
- (l) After a slight time delay, the brake is released.
- (m) The templet mounting structure moves up.
- (n) The stripper moves up to start stripping the article off the tool.
- (o) The templet mounting structure stops in proper starting relationship to the carriage.
- (p) The carriage and tailstock together move upwardly.
- (q) Finally the carriage and stripper are stopped in their fully up positions to complete a cycle of operation with the components of the machine positioned in readiness for the next cycle of operation.

I claim:

1. In a machine tool: a bed; a first support mounted adjacent one end of said bed; a spindle rotatably mounted on said support; a second support mounted adjacent the opposite end of said bed; a carriage disposed on said bed for movement over the bed in a direction generally along the rotational axis of said spindle; hydraulic piston and cylinder means for moving the carriage operatively interconnected between said carriage and said second support, the resultant operating force of said means acting along the axis of rotation of said spindle; a support member movably mounted on said carriage, the movement being in a direction generally along said rotational axis; hydraulic piston and cylinder means for moving said support member operatively interconnected between said carriage and said support member; two tracer templets each mounted on said support member; a rotatable tailstock mounted on said support member, the rotational axis of the tailstock being coaxial with the spindle axis; two roller rests respectively mounted on said carriage on opposite sides of the rotational axis of the spindle and each arranged for movement in a direction at an acute angle with respect to said rotational axis; a pair of hydraulic piston and cylinder means for moving the rests respectively operatively interconnected between said carriage and said rests, the resultant operating forces of last said means lying in a plane containing the rotational axis of the spindle; a pair of rollers respectively mounted on said rests; and two tracer valves respectively mounted on said rests and cooperating respectively with said templets to control fluid for last said piston and cylinder means.

2. A construction in accordance with claim 1 wherein said acute angle is 60°.

3. A construction in accordance with claim 1 wherein said bed includes at least a pair of tie-in columns interconnecting said first and second supports.

4. In a machine tool: a base; spaced framing connected to and extending upwardly from said base; a spindle rotatably mounted on said base, the rotational axis of the

- spindle extending upwardly; an end cap connecting said framing at the top thereof; a pair of flat plates disposed interjacent said framing; a central support block, the block being disposed generally along said rotational axis and interconnecting said plates; a pair of webbed members disposed on opposite sides of said rotational axis and interconnecting said plates, said flat plates, block and webbed members forming a carriage; guide means interconnecting the carriage and the framing to guide the carriage for up and down movement; hydraulic piston and cylinder means for moving the carriage operatively connected between said end cap and said central support block, the axes of the piston and cylinder means lying in a plane containing the rotational axis of the spindle and being located with respect to said rotational axis so that the operating force thereof is along said rotational axis; a support member movably mounted in said central support block; hydraulic piston and cylinder means for moving the support member operatively connected between said support member and said central support block; a pair of templet supports disposed on opposite sides of said rotational axis and being mounted on said support member for movement therewith; a pair of pistons respectively mounted on said webbed members, the axes of the pistons lying in a plane containing the rotational axis of the spindle and being oriented at an acute angle with said rotational axis; a pair of cylinders respectively movably mounted on said webbed members and respectively cooperating with said pistons, each cylinder being adapted to support a roller; and a rotatable tailstock mounted on said support member, the rotational axis of which is substantially coaxial with the rotational axis of said spindle.
- 5. In a machine tool: a base; first, second and third frames connected to and extending upwardly from said base, the frames being spaced apart and disposed generally at the vertices of a triangle; an end cap connecting said frames to the top thereof; a spindle rotatably supported on said base, the rotational axis of the spindle extending upwardly and being located substantially centrally of said triangle; front and rear spaced-apart, flat plates disposed between said frames and respectively on opposite sides of the rotational axis of the spindle; a central support block interconnecting said flat plates and being formed with a central aperture whose axis is generally coaxial with the rotational axis of the spindle; a pair of side supports disposed on opposite sides of said spindle axis and interconnecting said plates, the plates, the block and the side supports all being respectively tied together and forming a carriage; key and keyway means interjacent each of said plates and said block and said side supports; guide means interconnecting said rear plate and one of said frames to guide the carriage for up and down movement; a pair of pistons and cylinders for moving the carriage operatively disposed between said block and said end cap, the pistons and cylinders being symmetrically respectively disposed on opposite sides of said axis and lying in a plane containing said axis; a support member mounted in said aperture for up and down movement therein; piston and cylinder means for moving said support member operatively connected between said block and said support member; a rotatable tailstock mounted on said support member, the rotational axis of the tailstock being coaxial with said spindle axis; templet mount means carried in guide means on said front plate for up and down movement; a connection between said support member and said templet mount means to cause movement of the templet mount means with the support member; a pair of pistons respectively mounted on said side supports, the axis of the pistons lying in said plane and being oriented at an acute angle with said rotational axis; and a pair of cylinders respectively movably mounted on said side supports and respectively cooperating with last said pistons, each cylinder being adapted to support a roller.
- 6. In a machine tool: a spindle adapted to rotatably

support a blank to be worked, the spindle having a working surface; a carriage movable in a direction along the rotational axis of the spindle, the carriage including a pair of plate-like structural members respectively disposed on opposite sides of the rotational axis of the spindle and extending parallel one another, each member having substantial dimension in a direction parallel said axis, together with means rigidly connecting the plate members together; means for moving said carriage, the operating force of said means acting in a plane containing the rotational axis of the spindle; a roller rest movably mounted on said carriage interjacent said plate members and adapted to mount a roller, the rest being movable relative to said carriage generally in a direction making an acute angle with respect to said spindle axis; and means for controlling the movement of said rest, the operating force of last said means acting in said plane containing the rotational axis of said spindle, the movements of the carriage and rest causing the roller to move over said working surface for the working operation.

7. In a machine tool: a bed; a spindle rotatably mounted on said bed and adapted to mount a blank for a working operation; a carriage on said bed and mounted for movement in a direction along the rotational axis of said spindle, the carriage including a pair of plate-like structural members respectively disposed on opposite sides of the rotational axis of the spindle and extending parallel one another, each member having substantial dimension in a direction parallel said axis, together with means rigidly connecting the plate members together; means connected between said bed and said carriage for moving the carriage, the operating force of said means acting in a plane containing the rotational axis of said spindle; a pair of roller rests movably mounted on said carriage interjacent said plate members respectively on opposite sides of said axis, each rest being movable relative to said carriage along an axis directed at an acute angle with respect to said spindle axis and lying in said plane, the acute angle of each rest being the same; a pair of rollers for performing a working operation on said blank respectively mounted on said rests, each rest mounting its roller so that the roller, during the working operation, moves in and its force is transmitted through said plane; and mechanism respectively connected between said rests and said carriage and each mechanism providing for movement of its rest in said direction, the operating forces of said mechanisms acting in said plane and operative so that the movements of the rollers are symmetrical with relation to said spindle axis.

8. In a machine tool: a bed; a spindle rotatably mounted on said bed and adapted to mount a blank for a working operation; a carriage on said bed and mounted for movement in a direction along the rotational axis of said spindle, the carriage including a pair of plate-like structural members respectively disposed on opposite sides of the rotational axis of the spindle and extending parallel one another, each member having substantial dimension in a direction parallel said axis, together with means rigidly connecting the plate members together; means connected between said bed and said carriage for moving the carriage, the operating force of said means acting in a plane containing the rotational axis of said spindle and along said axis; a pair of roller rests movably mounted on said carriage interjacent said plate members respectively on opposite sides of said axis, each rest being movable relative to said carriage along an axis directed at an acute angle with respect to said spindle axis and lying in said plane, the acute angle of each rest being the same; a pair of rollers for performing a working operation on said blank respectively mounted on said rests, each rest mounting its roller so that the roller, during the working operation, moves in and its force is transmitted through said plane; and mechanisms respectively connected between said rests and said carriage and each mechanism providing for movement of its rest in said direction, the operating force of each mechanism acting along the said

rest axis and the mechanisms being operative so that the movements of the rollers are symmetrical with relation to said spindle axis.

9. In a machine tool: a vertically-extending bed; a spindle rotatably mounted on the lower end of said bed and adapted to mount a blank for a working operation, the rotational axis of the spindle extending vertically; a carriage guided on said bed for up and down movement along the rotational axis of the spindle, the carriage including a pair of plate-like structural members respectively disposed on opposite sides of the rotational axis of the spindle and extending parallel one another, each member having substantial dimension in a direction parallel said axis, together with means rigidly connecting the plate members together; piston and cylinder means connecting the carriage to the top of said bed and providing for up and down movement of the carriage and arranged so that the forces providing for said movement act substantially along and in a plane containing said axis; a pair of cylinder means movably mounted on said carriage respectively on opposite sides of said axis interjacent said plate members, the axes of the cylinders extending in a direction acute with said spindle axis and lying in said plane containing said spindle axis; a pair of piston means fixed on said carriage and respectively cooperating with said cylinders, the axis of each piston being coaxial with its cylinder; a pair of rollers for performing a working operation on said blank; and a pair of roller rests respectively carrying said rollers and connected with said cylinder means, each rest providing for the rotational axes of the rollers to lie in said plane and the operation of last said piston and cylinder means effecting movement of the rests.

10. In a machine tool: a bed; a spindle rotatably mounted on the bed and adapted to mount a blank for a working operation; a roller for performing a working operation on said blank; means for moving the roller over the surface of the spindle for the working operation comprising a carriage on the bed and movable to impart to the roller a component of motion along the rotational axis of the spindle and a roller rest carrying the roller and mounted on the carriage to impart to the roller a component of motion transverse said spindle axis; tracer means for controlling the movement of said roller rest including a templet and a tracer valve, the valve being mounted on said roller rest and cooperating with said templet; a templet mount means movably supported on said carriage and carrying said templet, the direction of movement being along said spindle axis; control means for controlling the movement of said templet mount means and providing for the mount to move with and independently of said carriage and for the mount to remain fixed while the carriage moves; means on said carriage operative at the start of the working operation to condition said control means so that said templet mount remains fixed while the carriage moves during the working operation; and means on said carriage operative after said working operation is completed to condition said control means to move the templet mount in a direction away from said spindle independently of carriage movement.

11. In a machine tool: a vertically-extending bed; a spindle rotatably mounted on the lower end of said bed and adapted to mount a blank for a working operation; a roller for performing a working operation on said blank; a carriage guided on said bed for up and down movement along the rotational axis of said spindle; a roller rest mounting said roller and mounted on said carriage for back and forth movement in a direction transverse said spindle axis, the movement of the carriage and the rest causing the roller to move over the spindle surface for the working operation; tracer mechanism for controlling the movement of the roller rest including a templet and a tracer valve, the valve being mounted on said rest and cooperating with said templet; a movable member mounted on said carriage, the direction of its movement being

along said spindle axis and the member being engageable with a blank mounted on said spindle at the start of a working operation and the templet being mounted on said member and movable therewith; control means to control the movement of said movable member on the carriage, the control means being connected between the carriage and the movable member and providing for the carriage and the movable member to be movable together, for the member to move independently of the carriage and for the member to remain fixed while the carriage moves when the member has engaged a blank mounted on said spindle; and means on said carriage operative after said working operation is completed to condition said control means to move the movable member in a direction away from the spindle independently of carriage motion.

12. In a machine tool: a bed; a spindle rotatably mounted on said bed and adapted to mount a blank for a working operation; a roller for performing a working operation on said blank; means for moving the roller over the surface of the spindle for the working operation comprising a carriage on said bed and movable to impart to the roller a component of motion along the rotational axis of the spindle and a roller rest carrying said roller and mounted on the carriage to impart to the roller a component of motion transverse said spindle axis; tracer means for controlling the movement of the roller rest including a templet and a tracer valve, the valve being mounted on said rest and cooperating with said templet; a support carrying said templet, the support being movably mounted on said carriage, the direction of movement being along said spindle axis, the support having rotatable means adapted to engage a blank mounted on said spindle; control means to control the movement of said support on the carriage, the control means being operatively connected between the carriage and the support and providing for the carriage and support to be movable together, for the support to move independently of the carriage and for the support to remain fixed while the carriage moves when the rotatable means has engaged a blank mounted on said spindle; and means on said carriage operative after said working operation is completed to condition said control means to move said support in a direction away from said spindle independently of carriage motion.

13. In a machine tool: a bed; a spindle rotatably mounted on said bed and adapted to mount a blank for a working operation; a roller for performing a working operation on said blank; means for moving the roller over the surface of the spindle for the working operation comprising a carriage on the bed and movable to impart to the roller a component of motion along the rotational axis of the spindle and a roller rest carrying the roller and mounted on the carriage to impart to the roller a component of motion transverse said spindle axis; tracer means for controlling the movement of the roller rest including a templet and a tracer valve, the valve being mounted on said rest and cooperating with said templet; and means for mounting said templet including a support member movably mounted on said carriage, a templet mount carrying said templet and movably mounted on said carriage and connected with said support member to be movable therewith, a rotatable tailstock on said support member and movable therewith, the tailstock being adapted to engage a blank mounted on said spindle together with control means including piston and cylinder means connected between said carriage and said support member and providing for the carriage and the support member to be movable together in a direction toward said spindle, for the support member to remain fixed when the tailstock has engaged a blank mounted on the spindle and the carriage moves for a working operation and for the support member to move in a direction away from said spindle independently of carriage movement after the working operation is completed.

14. In a machine tool: a bed; a spindle rotatably mounted on the bed and adapted to mount a blank for a working operation; a roller for performing a working operation on said blank; means for moving the roller over the surface of the spindle for the working operation comprising a carriage on the bed and movable to impart to the roller a component of motion along the rotational axis of the spindle and a roller rest carrying the roller and mounted on the carriage to impart to the roller a component of motion transverse said spindle axis; tracer means for controlling the movement of said roller rest including a templet and a tracer valve, the valve being mounted on said roller rest and cooperating with said templet; a templet mount means movably supported on said carriage and carrying said templet, the direction of movement being along said spindle axis; control means for controlling the movement of said templet mount means and providing for the mount to move with said carriage, for the mount to remain fixed while the carriage moves and for the mount to move independently of carriage movement; means on said carriage operative at the start of the working operation to condition said control means so that said templet mount remains fixed while the carriage moves during the working operation; and means on said carriage operative after a working operation is completed to condition said control means to effect movement of said templet mount means independently of said carriage in a direction away from said spindle.

15. In a machine tool having a rotatable spindle adapted to mount a blank and rollers to move over the spindle to work the blank, mechanism for mounting said rollers comprising: a pair of generally triangular-shaped, flat, spaced-apart plates; a pair of cross members respectively interconnecting opposite ends of said plates; a central support block connected between said plates generally centrally thereof, the block being formed with a plurality of collars each having flat sides respectively engaging said plates and the block being formed with a central aperture; key and keyway means between one of said collars and said plates; a pair of side supports connected between said plates respectively on opposite sides of said block, each side support having webs extending between said plates and also having a planar surface oriented at an angle with respect to the axis of said aperture; key and keyway means between said side supports and said plates; a pair of end blocks respectively connected to the planar surfaces of said side supports; a pair of cylinders respectively movably mounted on the planar surfaces of said side supports; a pair of pistons respectively cooperating with said cylinders and connected respectively to said end blocks; and a pair of roller blocks respectively mounted on said cylinders.

16. A construction in accordance with claim 15 wherein said key and keyway means provide for adjustment of said side supports in a direction transverse the axis of said aperture.

17. In a machine tool having a rotatable spindle adapted to mount a blank and rollers to move over the spindle to work the blank, mechanism for mounting said rollers comprising: a pair of generally triangular-shaped, flat, spaced-apart plates; a pair of cross members respectively interconnecting opposite ends of said plates; a central support block connected between said plates generally centrally thereof, the block being formed with a plurality of collars each having flat sides respectively engaging said plates and the block being formed with a central aperture and a slot extending through the block and along the axis of the aperture; a head connected to one end of said central support block and extending across said aperture; a generally cylindrical member mounted for back and forth movement in said aperture; piston and cylinder means connected between said cylindrical member and said head, the axis of the piston and cylinder means being coaxial with the axis of said aperture; a rotatable tailstock

mounted on said cylindrical member, the rotational axis of the tailstock being coaxial with the aperture axis; a pair of side supports connected between said plates respectively on opposite sides of said block, each member having webs extending between said plates and also having a planar surface oriented at an angle with respect to the axis of said aperture; a pair of end blocks respectively connected to the planar surface of said side supports, a pair of cylinders respectively movably mounted on the planar surfacing of said side supports; a pair of pistons respectively cooperating with said cylinders and connected respectively to said end blocks; a pair of rollers respectively mounted on said cylinders; a pair of tracer valves respectively connected with said cylinders; a tracer templet mount connected to one of said plates for movement back and forth in a direction along said aperture axis; a pair of tracer templets mounted on said support and respectively cooperating with said valves, the valves controlling fluid for said cylinders to control the movement thereof; and means extending through said slot and interconnecting said templet mount and said central support block.

18. In a machine tool:

a frame;
a spindle rotatably mounted on said frame and adapted to mount a blank for a working operation;
a carriage disposed on said frame for movement in a direction along the rotational axis of the spindle, the carriage comprising a pair of plate-like structural members respectively disposed on opposite sides of said axis and extending parallel one another, each member having substantial dimension in a direction parallel said axis, together with means rigidly connecting the plate members together;
mechanism on said frame and on at least one of said plate members slidably connecting the same to said frame and providing means to guide the carriage in said direction, the plates being spaced apart a distance to provide for movement of the carriage over said spindle;
a pair of side supports relatively disposed on opposite sides of said rotational axis and extending between and rigidly connected with said plate members;
a pair of roller rests respectively disposed interjacent said plate members on opposite sides of said rotational axis;
means respectively slidably connecting the roller rests with said side supports and providing for movement of each rest relative to the plate members in a direction transverse said rotational axis;
a pair of rollers for performing said working operation, the rollers being respectively mounted on said rests;
a central support block disposed between and rigidly connected with said plate members and being formed with a central aperture extending in a direction along and co-axial with said rotational axis;
a rotatable tail stock for clamping a blank on said spindle during a working operation; and
means movably mounting the tail stock in said block aperture and providing for relative motion between the tail stock and the block during a working operation, the relative motion being in a direction along said spindle rotational axis.

19. In a machine tool:

a rotatable spindle adapted to mount a blank for a working operation;
a pair of plate-like structural members respectively disposed on opposite sides of said axis and extending parallel one another, each member having substantial dimension in a direction parallel said axis, together with means rigidly connecting the plate members together;
mechanism interconnecting said spindle and at least one of said plate members and providing for relative motion between the spindle and the plate members in a direction along the rotational axis of the spindle including relative motion to a position wherein the spindle is disposed between the plate members, the plate members being spaced apart a distance to accommodate last said motion;
a pair of side supports respectively disposed on opposite sides of said rotational axis and extending between and rigidly connected with said plate members;
a pair of roller rests respectively disposed interjacent said plates on opposite sides of said rotational axis; means respectively slidably connecting the roller rests with both of said plate members and providing for movement of each roller rest relative to the plate members in a direction transverse said rotational axis;
a pair of rollers for performing said working operation, the rollers being respectively mounted on said rests; a rotatable tail stock for clamping a blank on said spindle during a working operation, the tail stock being disposed between said plate members and the rotational axis of the tail stock being co-axial with the rotational axis of the spindle; and
means movably connecting the tail stock with said pair of plate members and providing for relative motion between the tail stock and plate members during a working operation, the relative motion being in a direction along the rotational axis of the spindle.
